Inventor:

Ephraim Beeman.

UNITED STATES PATENT OFFICE.

EPHRAIM BEEMAN, OF OWEGO, NEW YORK.

IMPROVEMENT IN HAND-DRILLS.

Specification forming part of Letters Patent No. 36,135, dated August 12, 1862:

To all whom it may concern:

Be it known that I, EPHRAIM BEEMAN, of Owego, in the county of Tioga, State of New York, have invented a new and Improved Hand-Drill; and I do hereby declare that the following is a full and exact description thereof, reference being had to the accompanying drawing, and to the letters of reference marked thereon.

The nature of my invention consists in rotating a drill-stock, *d*, running in the brass frame *a b c D*, by means of a cord passed once or more around a wheel or pulley upon the drill-stock, also passing around the pulleys *A B c*, the cord having the proper tension given to it by means of the screw shown at *f*, which also serves the purpose of a handle to operate the cord, to which a back-and-forth movement is given. The drill *e* is easily removed to give place to other instruments.

To enable others skilled in the art to make and use my invention, I will proceed to describe its construction.

The drill-frame *a b c D* may be made of brass or iron. The drill-stock *d* should be of steel. The cord should be of gut or any other suitable material. There is one thing to be understood—that this instrument can be made in different ways for different purposes.

What I claim as my invention, and desire to secure by Letters Patent, is—

The manner of rotating a drill-stock by means of a cord passing around it and around pulleys, making it a convenient and durable tool, as above described.

EPHRAIM BEEMAN.
